UNITED STATES PATENT OFFICE.

WILLIAM H. SAUVAGE, OF DENVER, COLORADO, ASSIGNOR OF ONE-HALF
TO ABSALOM V. TABOR, OF CREEDE, COLORADO.

RAILWAY ELECTRIC SIGNAL AND SAFETY APPARATUS.

SPECIFICATION forming part of Letters Patent No. 698,143, dated April 22, 1902.

Application filed October 12, 1900. Serial No. 32,882. (No model.)

To all whom it may concern:

Be it known that I, WILLIAM H. SAUVAGE, a citizen of the United States of America, residing at Denver, in the county of Arapahoe and State of Colorado, have invented certain new and useful Improvements in Railway Electric Signal and Safety Apparatus; and I do declare the following to be a full, clear, and exact description of the invention, such as will enable others skilled in the art to which it appertains to make and use the same, reference being had to the accompanying drawings, and to the figures of reference marked thereon, which form a part of this specification.

My invention relates to improvements in railway electric signal and safety apparatus adapted for use in connection with air-brake systems, provision being made whereby when the circuit is closed the train-pipe is automatically tapped and the brakes applied. Provision is also made for automatically closing the throttle-valve at the same time the brakes are applied.

The invention will now be described in detail, reference being made to the accompanying drawings, in which is illustrated an embodiment thereof.

In the drawings, Figure 1 is a side elevation of a locomotive equipped with my improved signal and safety apparatus. Fig. 2 is a plan view of my block system for closing the circuit when two locomotives have approached within predetermined limits. Fig. 3 is an end view of a depending trolley attached to the locomotive and engaging the conductors intermediate the track-rails. In this view the parts are shown on an enlarged scale. Fig. 4 shows the trolley and its supporting bar or shaft on a smaller scale. Fig. 5 is an enlarged detail view of a box for supporting either end of the trolley-shaft. Fig. 6 illustrates the mechanism on the locomotive shown on a larger scale. Fig. 7 illustrates a portion of the mechanism on the locomotive shown on a scale still further enlarged.

The same reference characters indicate the same parts in all the views.

Let the numeral 5 designate the ordinary track-rails, between which is located a double

sectional conductor composed of parts 6 and 6^a of any desired length. The parts 6 and 6^a are arranged alongside of and insulated from each other. They are so arranged that the breaks or spaces between the extremities of one set of parts (6 or 6^a) are located opposite points midway between the extremities of the other set of parts. These parts 6 and 6^a are attached to plates 7, mounted on the ties 8, and are insulated from the ground and the track-rails. This double sectional conductor, composed of the parts 6 and 6^a, as aforesaid, forms a track midway between the rails for a depending trolley 9, composed of a roller 9^a, journaled in a frame 9^c. This trolley is suspended from a shaft 10, whose extremities engage boxes 12, mounted on the engine-frame. The trolley is loosely mounted, whereby it is arranged to swing slightly backward during the movement of the engine. The boxes 12 are insulated from the engine-frame.

From the trolley-frame leads a wire or electrical conductor 13 to the coils of an electromagnet 14. From the opposite extremity of the magnet-coils a wire 15 leads to a switch-contact 16. From another contact 17 a wire 18 leads to a telephone 19. From the telephone a wire 20 passes to a bell 21, from which a wire 22 leads to one pole 23 of a battery or electrical source 24. From the other pole 25 a wire 26 leads to the engine-frame, as shown at 27, and the circuit is grounded.

The space between the two contacts 16 and 17 of the switch may be bridged by a circuit-closer 28, pivotally mounted on the cab-frame. The magnet 14 is attached to the boiler-shell 29 or other suitable support. A movable bar 30 is connected with the core of the magnet-coil and is normally held in the position shown in Fig. 6 of the drawings by a coil-spring 31, one extremity of which is connected with a stationary part mounted on the cab-frame. The normal position of the bar 30 is farther to the left (see Fig. 6) than the position of the bar when the magnet is energized, since the energized magnet will cause its core to assume a central position in the coil, whereby the extremities of the core will protrude equally from the ends of the coil. The bar 30 is provided with an offset 30^a. The re-

duced portion of the bar to the right of the offset (see Fig. 6) normally engages the stem 33 of a valve 34, located within a chamber 35 and normally held against its seat 37 by a 5 spring 36. The valve 34 normally closes a port 38, leading to a chamber 39, through which the valve-stem 33 passes. The top of the chamber 39 is closed by a stuffing-box 40, through which the stem 33 also passes. From 10 the chamber 39 a pipe 41 leads to one extremity of a cylinder 42, provided with a piston 43, whose stem 44 passes through the stuffing-box in the end of the cylinder and is connected with a lever 45, which controls the 15 throttle-valve 46 of the engine. Normally or when the throttle-valve is open the lever 45 and the piston 43 are in the position shown in Fig. 6 of the drawings. The valve-chamber 34 communicates by way of a pipe 47 with 20 the train-brake pipe 48, through which the air passes to the air-brake mechanism, (not shown,) composed of the triple valve, the auxiliary reservoir, and the brake-cylinder. A 25 stop-cock 49, located in the pipe 47, is normally open, but may be closed to cut off the air from the chamber 34 when desired.

The circuit-closer 28 is normally in the position shown in dotted lines, Fig. 6, whereby the magnet is energized by a current through 30 the wire 13. A separate wire 50 leads from the wire 13 to the wire 18 to complete the circuit through the telephone 19 and the bell 21 when the circuit is broken at the switch—that is to say, when the circuit-closer 28 is in the position shown in full lines in Fig. 6.

The lever 45 for controlling the throttle-valve is provided with a sliding dog 45^a, whose lower extremity 45^c engages the notches of the quadrant 45^d. The dog 45^a is provided 40 with a roller 45^e, adapted to engage a rod 45^h, connected with the piston-stem 44. This rod 45^h is provided with an offset 45^j and rests upon the pin 45^k, attached to the lever, whereby the rod is supported in operative position. 45 This rod is also provided with a stop-pin 45^m, located some distance from the body of the lever when the throttle-valve is open. The cylinder 42 is provided with an escape-port 42^a, through which the air in the cylinder 50 passes after the piston 43 has reached its forward limit of movement or its limit of movement toward the right, referring to Fig. 6. The size of the port 42^a may be regulated to suit the purpose, according as it is desired to 55 make an ordinary stop or an emergency stop when the brakes are applied.

In describing the operation of the apparatus it must be understood that the engines or trains referred to are each equipped with 60 apparatus substantially identical with that already described. For convenience of description I will assume that the two track-sections 6 and 6^a are each a mile and a half in length. When the two trolleys 9, one belonging to each 65 engine, are both on the same section 6 or 6^a, as the case may be, the electric current will pass from the source of electricity 24 on the

one engine by way of the wire 22, the bell 21, the wire 20, the telephone 19, the circuit-closer 28, the wire 15, the electromagnet 14, the wire 70 13 to the trolley 9 of the engine and thence to the conductor-section 6 or 6^a, from which it passes to the trolley of the next engine and thence to the electromagnet, telephone, bell, and finally to the source of electricity, and 75 thence to the ground, completing the circuit. As soon as this occurs the signal-bell 21 will ring on each engine and each telephone will be put in the circuit ready for use. Moreover, as soon as the magnet 14 is energized the 80 bar 30 is shifted to the position shown in Fig. 7, forcing the valve-stem 33 downward by the engagement of the offset 30^a with the top of the stem sufficiently to open the valve 34, allowing the air to pass from the train-brake 85 pipe 48 by way of the branch pipe 47 into the chamber 35, through the port 38 into the chamber 39, and thence by way of the pipe 41 to the cylinder 42, which it enters in the rear of the piston 43. This piston is immediately 90 driven by the air-pressure forward or toward the right (see Fig. 6) to its limit of movement. The effect of this movement of the piston is first to actuate the rod 45^h sufficiently to cause the offset 45^j to pass under the roller 45^e, 95 whereby the dog 45^a is raised out of its notch in the quadrant 45^d. As soon as this occurs the pin 45^m engages the lever proper and actuates it sufficiently to close the throttle-valve. As soon as the piston has reached its limit of 100 forward movement in the cylinder 42 the air in the cylinder escapes through the port 42^a, reducing the pressure in the train-brake pipe sufficiently to apply the brakes to the train.

From the arrangement of the conductor-sections 6 and 6^a it is evident that the two trains cannot get nearer each other than one-half the length of the section, or three-fourths of a mile, without closing the circuit on the two trains, with the result that the bells are 105 rung, the telephones placed in the circuit, the throttle-valves closed, and the brakes applied to stop the trains.

After the danger is over and it is desired to release the brakes the circuit in which the 115 magnet is located is broken by shifting the circuit-closer 28 to the position shown by full lines in Fig. 6. The spring 31 will then return the bar 30 to its normal position, releasing the valve 34, which will then be seated by the recoil of the spring 36, thus cutting off the escape of air from the train-pipe 48. The throttle-valve may then be opened by returning the lever 45 to the position shown in Fig. 6. The circuit is still complete through 125 the telephone and signal-bell by way of the wire 50, allowing the engineers of the two trains to converse with each other as long as the engines are on the same block or their trolleys in contact with the same conductor-section 6 or 6^a.

The electromagnet 14 (shown in the drawings) consists of a solenoid whose movable core 14^a is connected with the bar 30, as shown

at 30°. The core of the solenoid is held by a spring farther toward the left than its normal position when the magnet is energized. When an electric current is passed through 5 the coils of the magnetic solenoid, the core is moved toward the right (see Fig. 6) sufficiently to accomplish the purpose heretofore explained.

In Fig. 1 a different spring arrangement is 10 illustrated from that shown in Figs. 6 and 7 and already described. In Fig. 1 the spring, which I will designate 31^a, surrounds the bar 30 and one extremity of the magnet-core. One end of the spring bears against the frame 15 or spool of the magnet, while the other extremity engages a stop on the bar 30. The tension of the spring 31^a is such as to maintain the relative arrangement of parts heretofore explained.

20 Having thus described my invention, what I claim is—

1. The combination with air-brake mechanism, a throttle-valve on the engine, and a hand-lever for controlling said valve, the 25 said lever being normally locked when the throttle-valve is open, of a cylinder mounted on the engine, a piston located therein, a connection between said piston and the hand-lever for unlocking the lever and actuating the 30 same to close the throttle-valve when the piston is actuated, an electromagnet mounted on the engine, a conduit connecting the train-brake pipe with the cylinder, a normally closed valve located in said conduit, a connection 35 between said valve and the magnet whereby the valve is opened as the magnet is energized, allowing the air to pass to the cylinder and actuate the piston, whereby the lever is unlocked and operated to close the 40 throttle-valve, the cylinder being provided with a port so located as to allow the air to escape after actuating the piston, whereby the necessary reduction is effected for setting the brakes.

45 2. The combination with a source of electricity carried by the train, of an electromagnet located on the engine and connected with said source, means located on the road-bed and connected with the magnet for energizing the same when trains have approached within a predetermined distance, a hand-lever for closing the throttle-valve on the engine, said lever having a removable device normally locking the lever in the adjusted position when the throttle-valve is open, a cylinder located on the engine, a piston in the cylinder, a rod connected with the piston, arranged to engage the hand-lever-locking device, and fashioned to unlock the same when 55 the piston is actuated, a conduit leading from a source of compressed air, to the cylinder, a normally closed valve located in said conduit, a connection between the valve and the elec-

tromagnet whereby as the latter is energized the valve is opened allowing the air to pass to 65 the cylinder whereby the piston is actuated and the hand-lever operated to close the throttle-valve.

3. The combination with air-brake mechanism, of an electromagnet carried by the train, 70 and provided with a movable core surrounded by the magnet-coil, a normally closed valve connected with the train-brake pipe and provided with a protruding stem, a part connected with the core of the magnet and provided with an offset arranged to engage the valve-stem and depress the latter to open the valve when the magnet is energized, a source of electricity carried by the train and with which the magnet is connected, and means 75 located on the road-bed and connected with the electric source, for closing the circuit when the trains have approached within a predetermined distance, whereby the magnet is energized, the valve opened and the air 80 allowed to escape, causing the necessary reduction of pressure to apply the brakes.

4. The combination with an electric source carried by the train, and means located on the road-bed and connected with said source for closing the circuit when two trains have approached within predetermined limits, and air-brake mechanism, of a hand-lever provided with a movable dog normally locking the lever when the throttle-valve is open, a cylinder, a piston located therein, a rod connected with the piston and provided with an offset arranged to raise and unlock the dog when the piston is actuated, and then actuate the lever to close the throttle-valve, a conduit 100 leading from the train-brake pipe to the cylinder, a normally closed valve located in said conduit, and provided with a protruding stem, an electromagnet provided with a movable core, a rod connected with said core and provided with an offset and a reduced portion, a spring normally holding the reduced portion of the rod in a position engaging the valve-stem, whereby the valve remains closed, the arrangement being such that when the magnet is energized, the rod is actuated to bring its offset in contact with the stem whereby the latter is depressed and the valve opened, allowing the air to pass to the cylinder and actuate the piston, and unlock and operate the 105 hand-lever, the cylinder being provided with a port allowing the air to escape after the piston has been actuated, whereby the necessary reduction of pressure is effected to apply the brakes.

110 In testimony whereof I affix my signature in presence of two witnesses.

WILLIAM H. SAUVAGE.
